W. G. DEXTER

COMBINED SWITCH AND FUSE

Filed March 8, 1922

Inventor
Wallace G. Dexter
By Pinelle Wright & Small
Attorneys

UNITED STATES PATENT OFFICE.

WALLACE G. DEXTER, OF BROOKLYN, NEW YORK.

COMBINED SWITCH AND FUSE.

Application filed March 8, 1922. Serial No. 541,899.

To all whom it may concern:

Be it known that I, WALLACE G. DEXTER, a citizen of the United States, a resident of Brooklyn, in the county of Kings and State of New York, have invented a certain new and useful Combined Switch and Fuse, of which the following is a specification.

This invention has as an object the construction of a combined switch and fuse which will involve less space, wiring and general cost of insulation than the usual forms of switches and connected fuses.

It has as another object the avoidance of the separation of the fuse from the switch, such as is the case when the fuse is mounted at the back of the switch-board. It has as a further object the provision of means for easily removing the fuse while the circuit is broken and inserting another fuse; and also the provision of means to prevent the removal of the fuse when the circuit is closed. Further objects will appear from the following description.

These objects are accomplished in the present invention of which the following description constitutes a preferred embodiment, reference being made to the drawings which form part of the specification. In said drawings,

Figure 1 represents a plan view of the combined switch and fuse for use in a complete circuit;

Fig. 2 shows a side view thereof, and

Fig. 3 shows the movable contact member in elevated position with the fuse disengaged from one of its holding members.

In this embodiment of the invention there is shown a combined knife switch and cartridge fuse designed to operate in a single closed circuit. The fixed contact members 1, 2 and 3, 4 of the knife switch are mounted on a base block 5 and a movable contact member denoted generally by 6 is pivoted at 7, 8 to the members 3, 4. This movable member is made up of a non-conducting cross or connecting piece 9 in which the pivoted conducting bars 10, 11 are fixed, and to this piece 9 is fixed a central rod 12 having pivoted thereto another rod 13 by means of a pivot at 14. A plunger 15 is fixed to the end of rod 13.

Mounted upon the structure first described and relatively movable with respect thereto, is another structure comprising a handle 16 attached to a cross-bar 17 of non-conducting character, which receives the ends of

conducting knives 18, 19 of the knife switch. The latter are connected to holding members 20, 21 provided with spring fingers to engage fuses 22, 23. The other ends of said fuses are received in rigid holding members 24, 25 which are preferably not yieldable. A spring 26 is inserted between the plunger 15 and a stop 27 on the handle 16 so that when they move relatively to each other the spring will have a tendency to force them back to their original positions.

In the operation of this device it will be apparent that when the switch is closed, as shown in Figs. 1 and 2, the current will run in one direction through fixed contact members 1, 3 and the fuse 22, and returned in the other direction through members 2, 4 and the fuse 23. When the circuit is broken, the fuse 22 will be broken and the fuse 23 will be intact. In this position the movable contact member 6 will be possible to pull the handle 16 out away from members 3, 4 against the resistance of the spring 26 to a point where the handle with its attached parts may be swung or tilted about pivot 14 as shown in Fig. 3, thus enabling the operator to remove the fuse 22 which has been retained by the spring fingers of the holding member 20. In this position the spring 26 will of course not be able to force the handle back to its original position, but when the handle is once more manipulated to bring the parts into alignment the spring will force the fuse back into the holding member 24 so that the movable contact member will again present a rigid structure. It will be evident that in this latter position the fuse cannot be removed by pulling it out, and when the movable contact member is brought down into contact with the fixed contact members the fuses cannot be removed at all since the handle 16 cannot be pulled out in the position shown in Figs. 1 and 2.

There are many advantages in the above described preferred embodiment, for no extra wiring is required; there is but little labor involved in installation; space is economized, and it becomes unnecessary for the operator to go to the back of the switch-board or elsewhere in order to determine the condition of the fuse or to remove it. Furthermore, in order to remove the fuse it is necessary to break the circuit, after which the removal of the old fuse and the insertion of the new one becomes an easy matter. The operation of breaking the circuit and pulling out the handle 16 may be con-

ducted in a single movement of the hand and arm of the operator, thus making the matter of attention and inspection of fuses a very simple and expeditious affair.

5 As many apparently widely different embodiments of this invention may be made without departing from the spirit thereof, it is to be understood that I do not intend to limit myself to the specific embodiment 10 thereof except as indicated in the appended claims.

I claim:

1. An electric switch comprising fixed contact members, a movable contact member associated therewith having portions respectively contacting with said fixed contact members, conducting clips interposed between said contacting portions of said movable contact member, means permitting relative movement between said conducting clips without disconnecting said movable contact member, and fuses held in position by said clips and disengageable therefrom by relative movement therebetween.

20 2. An electric knife switch comprising fixed contact members, a movable contact member pivoted to one of the fixed members, said movable contact member being made up of a non-conducting rod in fixed relation with the pivot, a second rod pivoted to the first mentioned rod in order to permit a tilting movement, a fixed fuse holder affixed to said non-conducting rod, means on said second rod carrying a fuse holder, said latter means being movable with respect to the fixed fuse holder to disengage the fuse and to permit a tilting movement of said second rod.

25 3. An electric knife switch comprising fixed contact members, a movable contact member pivoted to one of the fixed mem-

bers, said movable contact member being made up of a non-conducting rod in fixed relation with the pivot, a second rod pivoted to the first mentioned rod in order to permit a tilting movement, a handle mounted around said rods so that it may be moved along them to clear the pivot and permit a tilting movement, a movable fuse holder attached to the handle and a fixed fuse holder attached to the first mentioned non-conducting rod.

4. An electric switch comprising fixed contact members, a movable contact member associated therewith having portions respectively engageable with the fixed contact members, said movable contact member having relatively movable fuse holding means, means for removing the fuse by moving said holding means when the circuit is broken, and a spring for forcing the holding means back into position.

5. An electric knife switch comprising fixed contact members, a movable contact member pivoted to one of the fixed members, said movable contact member being made up of a non-conducting rod in fixed relation with the pivot, a second rod pivoted to the first mentioned rod in order to permit a tilting movement, a handle mounted around said rods so that it may be moved along them to clear the pivot and permit a tilting movement, a movable fuse holder attached to the handle, a fixed fuse holder attached to the first mentioned non-conducting rod, and a spring inside the handle arranged to force the said second rod back into position.

In testimony that I claim the foregoing, I have hereunto set my hand this 10th day of February, 1922.

WALLACE G. DEXTER.
